TRAFFIC MARKER FOR HIGHWAYS, OR THE LIKE

Harold A. Cannon, 2180 Yale Ave., Camp Hill, Pa.

Filed Feb. 17, 1960, Ser. No. 59,430

Term of patent 3½ years

(Cl. D72—3)

Figure 1 is a perspective view of a traffic marker for highways, or the like, embodying my new design;

I claim:

The ornamental design for a traffic marker for highways, or the like, as shown and described.
